Application January 10, 1934, Serial No. 706,021

10 Claims. (Cl. 179—107)

This invention relates to acoustic devices and more particularly to a bone conduction telephone receiver.

An object of this invention is to improve the efficiency and operating characteristics of the bone conduction type receiver.

One feature of this invention comprises a receiver having a bone actuating member supported by a pair of spaced resilient members.

10 A further feature comprises such a receiver in which the magnet structure is clamped between the resilient members.

A telephone receiver in accordance with this invention comprises, preferably, a pair of non-magnetic frame members supporting a pair of straight bar permanent magnets in spaced relation, a pair of pole pieces preferably T-shaped, the ends of the magnets engaging the ends of the cross bars on the pole pieces, the tails of the 15 pole pieces being bent at an angle to provide cores for an energizing winding. An armature is supported in spaced relation to the pole pieces being secured to the center of a resilient spring or restoring member preferably a Z-shaped strip 20 of spring metal. A similar resilient member is clamped between the magnet structure and one frame member. A vibrations conducting rod is secured at each end to these resilient members and is provided at one end with a button-shaped member adapted to be placed against the bony 25 portions of the user's head, preferably against the mastoid eminence. A suitable casing having an aperture through which the button extends provides an enclosure for the structure.

30 A more complete understanding of this invention will be obtained from the detailed description which follows, read with reference to the appended drawing, wherein:

40 Fig. 1 is a sectional view of an acoustic device embodying this invention;

Fig. 2 is a sectional view of the same device along the line 2—2 of Fig. 1;

45 Fig. 3 is a plan view of the device of Fig. 1 along the line 3—3 thereof with the cover member removed;

Fig. 4 is a perspective view of a fragment of the device of Fig. 1, partly exploded and partly broken away; and

50 Fig. 5 illustrates how the acoustic device shown by Figs. 1 to 4 is used.

The acoustic device herein disclosed comprises a bone conduction receiver designated generally as 10. This receiver comprises a casing or enclosure 11, preferably of insulating material,

having a substantially flat or planar wall portion 12 containing an aperture 13, and having a substantially rectangular open end normally closed by a cover, plate or removable wall member 14 secured to the casing rim 15 by any suitable means, for instance, screws 16. The casing contains a pair of non-magnetic frame members 17, 18. Frame member 17, preferably of insulating material, comprises a substantially flat or planar portion 19 and a vertically projecting end portion 20 in which terminal members 21 are embedded. The member 17 supports a pair of T-shaped pole pieces 22, for instance, of magnetic iron, the tail portions 23 of which are bent at an angle to the cross-bar portions 24 to provide cores 25 for an energizing winding 26 comprising coils 27. The free ends 28 of the energizing winding are terminated at the screw members 29 which thread into the terminal members 21. The receiver is connected with an electrical signaling circuit through the conductors 30, the tips 31 of which make a force fit engagement with similarly shaped passages in the terminal members. A pair of straight bar permanent magnets 32, preferably of cobalt steel, have their end portions resting on the extremities of the cross bars 24, one magnet being on each side of the pole pieces. The frame member, for instance, of aluminum, rests on the magnets 32 which, with the pole pieces, are clamped between the members 17, 18, for instance, by screw members 33 which extend through the member 17, openings 34 in the pole pieces and thread into tapped drilling 35 in the member 18.

35 A resilient, spring or restoring member 36, for instance, of phosphor bronze and substantially Z-shaped, having strip end portions 37 secured, for instance, by screws 38, to flange end portions 39 of member 18 and a substantially diagonally disposed curved strip portion 40 connecting the strip end portions supports an armature 41 of magnetic material, for instance, magnetic iron, substantially at its mid-portion and in spaced relation to the pole faces 42 of the pole pieces. 40 A similarly shaped resilient member 43 is clamped between frame member 17 and the pole pieces, the diagonally disposed portion 44 thereof, however, curving in direction opposite to that of portion 40.

45 A vibrations conducting rod or elongated member 45 connects the resilient members 36, 43 and has a threaded end portion 46 extending into an opening 47 in the frame member 17 in alignment with the aperture 13. A member 48 50

to be placed in contact with the head of a user, preferably at the mastoid eminence, and comprising a flat enlarged button-shaped portion 49 and a cylindrical stub portion 50 is provided 5 with a tapped drilling 51 for engagement with the rod end portion 48.

The bone conduction receiver 10 is mounted behind the ear with the member 48 resting against the mastoid eminence and may be supported on the head, as illustrated by Fig. 5, by a strap or other member 52, for instance, of spring metal.

Although this invention has been disclosed with reference to a single embodiment, it will 15 be understood that various modifications thereof may be made without departing from the scope of this invention which is to be considered as limited by the appended claims only.

What is claimed is:

- 20 1. An acoustic device comprising a magnet, pole pieces, an energizing winding, an armature, a resilient member supporting said armature in spaced relation to said pole pieces and having a curved diagonally disposed portion to the mid-portion of which said armature is affixed, a vibrations conducting rod connected at one end to said armature and having a bone contacting member at its other end, and a second resilient member attached to said rod near its bone contacting member.
- 25 2. An acoustic device comprising frame members, a magnet structure comprising a pair of straight bar permanent magnets and a pair of T-shaped pole pieces clamped between said frame members, an energizing winding on said pole pieces, a pair of spring members on opposite sides of said magnet structure, an armature carried by one of said spring members in spaced relation to said pole pieces, a vibrations conducting rod extending between and secured to said spring members, and means secured to one end of said rod for engagement with the head bones of a user.
- 30 3. A bone conduction receiver comprising an armature, means for actuating said armature, resilient means supporting said armature, other resilient means in spaced relation to said first mentioned resilient means, said resilient means comprising substantially Z-shaped strips of spring metal, and means connecting said resilient means, the means connecting said resilient means being joined thereto substantially at the mid-portions of the strips.
- 35 4. A bone conduction receiver comprising an armature, means for actuating said armature, resilient means supporting said armature, said resilient means comprising parallel strips of spring metal, one end of each of which is joined by a substantially diagonally disposed strip of spring metal, and means movable with said armature and resilient means for engagement with the head bones of a user.
- 40 5. A bone conduction receiver comprising frame members, a magnet structure comprising a pair of straight bar permanent magnets and a pair of T-shaped pole pieces clamped between said frame members, an energizing winding on said pole pieces, resilient means on opposite sides of said structure, an armature supported by the resilient means on one side of said structure, a vibrations conducting rod extending between and secured to said resilient means, and means

secured to said rod for engagement with the head bones of a user.

6. A bone conduction receiver comprising an armature, a magnet structure comprising a pair of straight bar permanent magnets, and a pair of T-shaped pole pieces, the cross bar of each pole piece engaging one end of each bar magnet and the tail of each pole piece being bent at an angle to the cross bar thereof, an energizing winding surrounding the bent portions of said 10 pole pieces, and a vibrations conducting member for engagement with the head bones of a user, said conducting member being movable with said armature.

7. A bone conduction receiver comprising, a 15 casing having an aperture in one wall and provided with a cover member, and a unitary assembly in said casing comprising an L-shaped support of insulating material, a Z-shaped spring member on the horizontal portion of said support, a pair of T-shaped pole-pieces, the cross bars thereof resting on the parallel end portions of the spring member and the tails thereof being bent at right angles to the spring member, an energizing winding surrounding said bent 20 portions of the pole-pieces, a pair of straight bar permanent magnets resting on the bars of the pole-pieces, one on each side of the pole-pieces, a frame member of non-magnetic material mounted on said magnets, fastening means 25 for securing together said support, spring members, pole-pieces, magnets and frame member, a second and similarly shaped spring member fastened to said frame member, an armature secured at the mid-portion of said second spring 30 member in spaced relation to said pole-pieces, and a rod member terminating in a button-shaped portion positioned in the aperture in the casing wall and being secured near opposite ends to said spring members. 40

8. A bone conduction receiver as claimed in the preceding claim in which terminal members are embedded in the vertical portion of said insulating support, the energizing winding being connected to said terminal members, and the 45 unitary assembly is held in said casing solely by said cover member.

9. A bone conduction receiver comprising an armature, a magnet structure comprising a pair of straight bar permanent magnets, a pair of 50 pole-pieces, each having angularly disposed portions, like portions of each pole-piece being adjacent one end of a bar magnet, an energizing winding on said pole-pieces, and a vibration conducting member for engagement with the head 55 of a user, the armature and the conducting member being secured together.

10. An acoustic device comprising a magnet, pole-pieces, an energizing winding, an armature, a resilient member supporting said armature in 60 spaced relation to said pole-pieces and having a curved diagonally disposed portion to the mid portion of which said armature is affixed, a vibrations conducting rod connected at one end to said armature and having a bone contacting 65 member at its other end, and a second resilient member attached to said rod near its bone contacting member, having a curved diagonally disposed portion to the mid portion of which the rod is attached and curving in direction opposite 70 that of the curved portion of the first-mentioned resilient member.

JOHN R. ERICKSON.
